POWDERED SOAP DISPENSER

Robert R. D. Milligan, Portland, Ind.

Application October 20, 1954, Serial No. 32,741

Term of patent 14 years

(Cl. D4—3)

Fig. 1.

Fig. 2.

Fig. 3.

Fig. 4.

To all whom it may concern:

Be it known that I, Robert R. D. Milligan, a citizen of the United States of America, residing at Portland, State of Indiana, have invented a new, original, and ornamental Design for a Powdered Soap Dispenser, of which the following is a specification, reference being had to the accompanying drawing, forming a part hereof.

I claim:

The ornamental design for a powdered soap dispenser, as shown.
